UNITED STATES PATENT OFFICE.

R. GUY COWAN, OF LAKEWOOD, OHIO.

DESIGN FOR A FLOWER HOLDER.

Application filed February 16, 1928. Serial No. 25,462. Term of patent 7 years.

To all whom it may concern:

Be it known that I, ROBERT GUY COWAN, a citizen of the United States, residing in Lakewood, in the county of Cuyahoga and the State of Ohio, have invented a new, original, and ornamental Design for Flower Holders, of which the following is a specification, reference being had to the accompanying drawing, forming part thereof.

The figure is a perspective view of a flower holder, showing my new design.

I claim:

The ornamental design for a flower holder, as shown.

R. GUY COWAN.
